UNITED STATES PATENT OFFICE.

EUGEN WÖLNER, OF LIVERPOOL, COUNTY OF LANCASTER, ENGLAND.

WEIGHING-MACHINE.

SPECIFICATION forming part of Letters Patent No. 294,713, dated March 4, 1884.

Application filed August 13, 1883. (No model.) Patented in England February 22, 1883, No. 977, and in Belgium September 17, 1883, No. 62,615.

To all whom it may concern:

Be it known that I, EUGEN WÖLNER, a subject of the King of Norway, residing at Liverpool, in the county of Lancaster, in the 5 Kingdom of England, have invented certain new and useful Improvements in Weighing-Machines, (for which I have received Letters Patent in England, dated February 22, 1883, No. 977, and in Belgium, dated September 17, 10 1883, No. 62,615, and for which I made application for Letters Patent in Germany on or about the 14th day of September, 1883, and which have not yet issued,) of which the following is a specification.

15 My invention relates to a weighing-machine in which a pendulous lever provided with an indicator to move over a dial is raised by the weight applied to the platform, the pendulous lever being furnished with a cylinder which 20 moves relatively to a fixed piston fitting loosely within the cylinder, whereby undue oscillation of the lever and indicator is prevented.

This invention is set forth in the accompanying drawings.

25 Figure 1 is a front elevation and part section of my apparatus; Figs. 2 and 2^a, a sectional side elevation; Fig. 3, a transverse section on the line *x x* of Fig. 4, showing indicating apparatus; Fig. 4, a part plan of apparatus; 30 Fig. 5, an enlarged sectional plan on line *y y* of Fig. 1. Figs. 6, 7, 8, and 9 are respectively an elevation, plan, and part side elevations of diagonal arm. Figs. 10, 11, and 12 are 35 respectively a plan, front, and end elevations of beam with diagonal arm in position; Fig. 13, a transverse section of beam; Figs. 14, 15, 16, enlarged sections of stool.

In the drawings, A is the weighing table or 40 platform. This rests on the stool B, which is provided with four pairs of legs, B', one pair at or near each corner resting on the round shafts 45 *e'*. These shafts ride on the stirrup-links *e'*. These stirrup-links are hooked onto the saddle-links *e*, which in turn are mounted on the knife-edges *e²* of the load-arms C⁵ of the lever-beams C² C³. The said stirrup-links *e'* and saddle-links *e*, being hook-shaped, can be unhooked or dismounted without disturbing or removing the knife-edges *e²*.

50 C² C³ are lever-beams of cruciform section,

this form being the best to resist the strains it is required to withstand, and the easiest to mold. These lever-beams are supported at their hanger-shaped or elbow-shaped ends G, and are provided with knife-edges forming 55 fulcrums. The ends of these beams being elbow-shaped, and the center of gravity of the cross-section being in the line of the fulcrum-edges at G, the motion will be a swinging or 60 rocking one in stable equilibrium—a great advantage, only gained by this arrangement. The load-arms C⁵, with their knife-edges, are on the inner side of the fulcrum knife-edges at G, thereby dividing the load on the fulcrum-supports, and thereby also entirely preventing any 65 tipping action of the lever-beams. The power is transferred from one lever-beam to another or equalized between them by means of the bar E, preferably adjustable as regards length by right and left handed screws and nut E'. 70 This is supported at each end on knife-edges F F on the arms C C', one of said arms being on the under side of beam C², and the other on the upper side of beam C³. There can be 75 more than one of these bars and corresponding knife-edges and arms, if required. The major lever-beam C⁵ is provided with a circular rim, C⁶, as shown in Figs. 10, 11, 12, and 13, and the lever-arm C⁴ with a correspondingly-curved flange to fit said rim. The rim is provided with a row or two rows of slot-holes extending horizontally all round the rim, and the lever C⁴ can be fixed to any point of the segment of the circle by bolts passing 80 through said slot-holes and flange. Its upper and lower halves on opposite sides of the center line are similar. In consequence of 85 this arrangement, one pattern of an arm, C⁴, can be used for a great variety of machines, and being made reversible it will do for right-handed or left-handed machines. In adjusting, the arm is slid round the rim till under 90 the point of suspension, or till the knife-edge at the point of suspension is square with the other series of knife-edges in the machine. It is then bolted. For the still further adjustability of the major lever C⁵, it is provided with a loose muff fitted over its extreme end, and capable of being moved along the end of the 95 said lever-arm, its position being regulated by 100

adjusting-screw C'. The muff C⁸ is provided with a round rim, C⁹, having slot-holes in a horizontal line for the fastening-bolts C¹⁰, used for securing the short piece C¹¹, in which is bedded the suspension knife-edge for the lever-arm C'. This short piece is provided with a circular flange to suit the rim of the muff, and is fastened by bolts thereto. By this arrangement the position in relation to the length or breadth of the weighing-machine can be regulated, so as to get the correct weighing-length for the lever, and the knife-edge at the point of suspension can yet be adjusted square with the other knife-edges. The lever C' transfers the power to the suspension-rod G', which is hooked onto the shackles g g', hung from the knife-edge h on the arm h³ of the compound lever H of the indicating apparatus. This arm can be one and the same with arm h², if desired.

The indicating apparatus shown in Figs. 3 and 4 consists of bell-crank-lever H, carrying a sliding weight, I, on the arm h¹, having a scale for adjusting said weight. This weight is used for weighing off the tare, and also on the said arm h¹, at the extreme end, is the counterbalance-weight I', by which the indicating apparatus is brought to zero. Another arm of same bell-crank lever H (marked h²) hangs down at a steep angle into a cistern, J, of liquid, and is provided with a counterpoise consisting of a heavy and nearly-closed tube, K, working over a fixed piston, L', of rather less area than the tube, and leaving very little passage-way for the liquid, which thus acts as a fluid cushion against too rapid movement of the tube, and thus prevents sudden jerks or oscillations.

Instead of the cylinder being movable and the piston fixed, the reverse could be the case; but I prefer the arrangement described. Preferably I form the pendulous tube in the form of a curved cylinder tube or box, K, with a curved piston-rod, L, passing through it, and fitted with a very loose-fitting piston, L', working in the said box or cylinder. The liquid in this case acts as a cushion, entering at the orifices round the piston-rod, and also passing round the piston in the cylinder, the small passage-ways allowing the cylinders only to move slowly, thus checking violent oscillations. On the axis of the bent lever H, I fix the lever h³ from the knife-edge h, on which the shackles or rings g g', connecting it with the lever system, are suspended. The rod G', connecting the indicating apparatus with the system of levers, is preferably hooked onto a shackle, g, suspended from a ring, g', or its equivalent, on the knife-edge h. The hooked suspension-rod G' has a second hook, r, Figs. 3 and 5, the one taking into the shackle or its equivalent. Below this second hook is a crank, R, and shaft R', worked by a hand-wheel, R². The shaft is locked in either position by pin-catch R³. If the hand-wheel be turned, the crank is raised and lifts the suspension-rod G' with the mechanism by the lower hook till the first hook is

lifted out of the shackle, and thus all connection between the indicating apparatus and the platform is cut off; but the platform is allowed to rest on its frame-work, instead of on the knife-edges e.

To put the apparatus in gear, a single turn of the hand-wheel carries the crank round, and the latter carries the lower hook, lifts it, and guides it until it leaves the first or upper hook in its shackle, and ready again for work. A stop-catch or locking device of any ordinary construction is used to lock the shaft R' in place when not requiring movement.

Returning now to the indicating apparatus, on arm h¹, which can be a mere extension of the tare-arm beyond the fulcrum, I fix a chain, M. This passes round the axis of pointer-wheel O, which axis is provided with a chain-wheel, teeth, or projections to interlock with the chain and prevent it slipping. A weight, Q, keeps the chain tight. On the end of arm h¹ is a scale or dial with degrees, showing the major weights, and on the rigid frame a hand or pointer indicating the weight as the scale oscillates past it. On the same dial are a series of scales, h⁵, so arranged that the minor weights are read off by the fingers of the finger-wheel O pointing to them, the position of these minor scales being so arranged that the combined motion of the ends of the pointers of the wheel and that of the dial shall always keep a scale exactly opposite the point of the pointer-wheel, and as one pointer leaves the end of one scale the other pointer arrives at the beginning of the next scale.

The mode of action is as follows: We will suppose the machine disconnected and at rest, and a cart of unknown weight arriving to have its tare taken, preparatory to loading. The attendant unlocks the shaft R' and turns it round; the crank R rises and engages in hook r and raises it, turning round with it till it brings the upper hook over the shackle g, and continuing the revolution, descends, leaving hook r in shackle g; still further descending, it leaves hook r. The machine is now connected, the cart is backed on, and its weight found by moving the tare-weight I on the arm h¹. The tare-weight is then clamped in this position. The cart now returns loaded, and, arriving on the platform, causes the indicator bell-crank lever H to move. Arm h¹ rises, the major weights are read off at h⁶, and the minor on the smaller scales by means of pointers of pointer-wheel O.

I am aware that grain-scales have been provided with a cylinder having valved inlets and outlets to be actuated or controlled by the tipping beam and a closely-fitting piston within said cylinder, the whole forming a brake to retain the beam in a lowered position while all the contents of its bucket are being removed. This I do not claim or use. My construction includes no valves, but merely a cylinder and a loose-fitting piston, which together act in much the same manner as a

dash-pot in other machinery, and serve to prevent violent oscillations of the indicator, which would otherwise occur.

I am further aware that in a dynamometer a pivoted beam has been furnished with a dash-pot at one end, and connected at the opposite end with a gravitating indicator-arm by a chain; but in that case the dash-pot had no immediate connection with the indicator, but separate and special means independent of said dash-pot were furnished to prevent sudden or violent oscillations of the indicator.

I claim as my invention—

1. In a weighing-machine, the combination 15 of the series of stirrup-links e' , supporting the weight of a series of saddle-links, e , carrying the same, the knife-edges e^2 , load-arms C^3 , and lever-beams $C^2 C^3$, linked together, by which means the load is well and evenly distributed.
2. The lever-beams $C^2 C^3$, with hanger-shaped ends provided with knife-edges G , upon which they are supported on their central axis of gravity, whereby a swinging or rocking motion in stable equilibrium is produced.
3. The combination of the lever-beams $C^2 C^3$, having their respective arms $C C'$, one under and the other above said beams, respectively, and carrying knife-edges $F F'$, with the adjustable link E .
4. In a weighing-machine substantially such as described and shown, the combination of a lever-beam, C^3 , provided with a circular rim, C^6 , and lever-arm C^4 , having a flange curved to fit said rim and secured thereto, substantially as and for the purpose explained.
5. In a weighing-machine substantially such as described and shown, the lever consisting of the major lever-beam C^3 , having circular rim provided with slots, and lever-arm C^4 , provided with a circular flange fitting the rim of beam C^3 , and secured thereto by bolts passing through the flange and the slots of the rim, whereby the lever-arm C^4 is adapted to be adjusted to any angle relatively to beam C^3 .
6. In a weighing-machine substantially such as described, the combination of lever-beam C^3 , provided with rim C^6 , and the reversible lever-arm C^4 , applied thereto, substantially as and for the purpose explained.
7. In a weighing-machine substantially such as described, the combination of transfer-lever C^4 with the loose muff C^8 , fitted upon the end of said lever and provided with a set-screw, and an arm, C^1 , provided with suspension knife-edges and adjustably secured to said muff, whereby the knife-edges may be brought into the exact position required to make connection with the rod which connects with the indicating devices.
8. In a weighing-machine substantially such as described and shown, the combination of transfer-lever C^4 and rod G' , the loose muff C^8 , having a rim, and a short arm adjustably bolted to said rim and provided with suspension knife-edges, whereby said knife-edges are adapted to be set at any required angle with the lever.

9. In a weighing-machine, the combination of a swinging indicator, a cylinder, and a piston fitting loosely within the cylinder, said cylinder and piston being secured one to the frame of the machine and the other to the swinging indicator, substantially as and for the purpose set forth.

10. The combination, in a weighing-machine, of the counterpoise-arm h^2 with the box K , the loosely-fitting piston L' , and the chamber of liquid, J , substantially as and for the purposes described.

11. In a weighing-machine, substantially as described, the combination, with a movable arm, h^2 , thereof, of cylinder K , carried by said arm, and stationary piston L' , of smaller diameter than the interior of the cylinder, substantially as described and shown, whereby the movements of said arm are guided, the parts are cushioned against jar and concussion, and violent oscillations of the indicator are prevented.

12. The combination of the counterpoise-cylinder oscillating on lever-arm h^2 , the curved piston-rod L , and the piston L' , fitting loosely in the counterpoise-cylinder, but rigidly attached to the piston-rod L , with the cistern of liquid, J , substantially as described.

13. The relieving apparatus consisting of the hand-wheel R^2 , shaft R' , and crank and crank-pin R , capable of engaging into hook r as the hand-wheel is actuated, whereby the hook r is raised and brought forward till the hook r hooks into shackle $g g'$, where it is left, when the crank-pin, continuing its forward revolution, falls again, and the reverse action takes place when the crank is turned the reverse way.

14. The combination of the suspension-rod G' , having two hooks—one the terminal or suspension hook and the other the relieving-hook—with a device for lifting the rod G' out of position by lifting hook r , and a stop, R^3 , for holding said device in any position.

15. The lever carrying on its respective arms a balance-weight and scale for showing tare, a set of indicator-scales, the pull of a system of levers from the platform, and, lastly, a weight hanging at a steep inclination below the axis of the lever.

16. The combination, with a lever carrying the pull of a system of levers, of the weighing-scale on one arm, a weight on a nearly-vertical arm, a series of scales attached to an arm, and the finger-wheel O , worked by gear from said lever, and so geared that each of the fingers of the wheel shall indicate in succession, on the moving scales, the smaller increments of weight, while a stationary pointer, h^1 , shall indicate the large weights, substantially as set forth.

17. The combination of lever h^4 , weighted chain M , and finger-wheel O with the series of scales h^6 and stationary pointer h^7 , substantially as and for the purposes described.

18. In a weighing-machine, the combination, with an arm, h^4 , oscillating (with differences of weights to be weighed) beside a sta-

tionary frame, the one (arm or frame) carrying a pointer and the other a scale for that pointer, of a conductor of motion—such as chain M—giving motion to the axle of a wheel revolving alongside of the lever, so as to greatly multiply the motion of the wheel relatively to the lever, by which means, with a pointer or series of pointers on one and a series of scales or a scale on the other, the minor weights can be read off through the movement of the wheel in reference to the lever, and the major weights by the movement of the lever in reference to the stationary frame.

19. In a weighing-machine substantially such as described, the combination, with a lever-beam, C¹, of a transfer-arm adjustably secured thereto, whereby it is adapted to be set at different angles to suit different sizes and forms of weighing-machines.

20. In a weighing-machine, the combination

of a diagonal lever, C¹, fitted with circular flange, and connecting the levers supporting the table or platform A to the indicating apparatus, with a circular flange, C², fixed to the center of the beam C¹, to which flange the flange of lever C is attached by a bolting device, by which means the length of the arm C¹ and distance between C² and the indicating apparatus can be indefinitely increased without altering the amount of leverage and weighing of the machine or the patterns of the various levers.

In testimony whereof I have signed my name to this specification in the presence of two subscribing witnesses.

EUGEN WÖLNER.
